UNITED STATES PATENT OFFICE.

SIGISMUND FISCHER, OF NEW YORK, N. Y.

ELECTRIC CLOCK.

SPECIFICATION forming part of Letters Patent No. 603,232, dated April 26, 1898.

Application filed June 26, 1897. Serial No. 642,386. (No model.)

To all whom it may concern:

Be it known that I, SIGISMUND FISCHER, a citizen of the United States, residing in the city, county, and State of New York, have 5 invented certain new and useful Improvements in Electric Clocks, of which the following is a specification.

This invention relates to certain improvements in the electric clock for which Letters 10 Patent No. 555,313, dated February 25, 1896, were granted to me, said improvements being designed with a view of improving the driving mechanism of the going-train of the clock, the regulation of the motion of the minute,

15 and seconds hands, and the synchronizing of said hands by a switch operated either by hand or automatically from a master-clock whenever the minute and seconds hands arrive at zero.

20 My invention consists of an electric clock having a synchronizing electromagnet and an arm extending radially from the minute-hand arbor and provided at its outer end with an armature adapted to be attracted by said 25 magnet for moving the minute-hand forward or backward to a given point of time, so as to synchronize with a master or other clock; and the invention consists of certain features of construction and combinations of parts to 30 be hereinafter described and then particularly claimed.

In the accompanying drawings, Figure 1 represents a front elevation of the clock-motion 35 of my improved electric clock with the dial removed and some parts broken away, so as to show the operating parts beneath the same. Fig. 2 is a side elevation of Fig. 1. Fig. 3 is an elevation of the going-train of my improved clock, partly in section on line 3 3, Fig. 2, and showing the driving mechanism of the clock. Fig. 4 is a detail of the mechanism by which the electric impulses are imparted to the pendulum. Fig. 5 is a detail front view of the synchronizing device 45 for the seconds-hand. Figs. 6 and 7 are top views of the same, showing the same respectively in normal position and in the act of synchronizing. Figs. 8, 9, 10, and 11 are details of the mechanism for alternately throwing 50 the different batteries by the current of which the clock is driven into action. Figs. 12, 13, and 13^a are details of the driving mech-

anism. Figs. 14, 15, 16, 17, 18, and 19 are additional details, drawn on a larger scale, of the synchronizing mechanism of the seconds-hand. Figs. 20 and 21 are a vertical transverse section and a front elevation of the synchronizing mechanism of the minute-hand, and Fig. 22 is a diagram showing the electric connection of the clock and synchronizing devices with the batteries by which electric current is supplied.

Similar letters of reference indicate corresponding parts.

Referring to the drawings, A represents the 65 frame of my improved electric clock, which is supported on an iron casting or plate B, which is screwed to wooden back of the clock-case. From a horizontal support b at the upper part of the casting B is suspended the pendulum P in the usual manner. The pendulum-rod is engaged by a pin C' on a crutch C, the upper end of which is attached to a spindle d, that turns in bearings of the supporting-frame A. On the spindle d is mounted a bar 70 armature E', which is arranged between the pole-faces of an electromagnet E, that is attached to the casting or supporting-plate B of the clock. The ends of the armature E', as well as the pole-faces of the electromagnet 75 E, are made equidistant from either side of the axis of the spindle d, so that the ends of the armature can pass by said pole-faces as the armature is oscillated by the beats of the pendulum.

85 On the crutch C is arranged a pin F, which is made wedge or knife edged and adapted to engage a notched or bifurcated pendant F', which is pivoted to the inner end of a fulcrumed contact-lever F², the outer end of 90 which is provided with a platinum point f², that presses on a contact-spring f³ whenever the pendant engages the pin F on the crutch, said contact-spring being insulated from the clock-frame by the insulating-block f⁴, on 95 which it is fixed. One bifurcation of the notched pendant is made somewhat longer than the other bifurcation, so that the pendant is only engaged by the pin F when the pendulum moves in one direction, but cannot 100 be engaged by the return beat of the pendulum. A light spring F⁵, supported at one end on the frame A, bears by its free end on the contact-lever F² in such a manner as that

in case of the pivots being clogged by oil or otherwise there will be a perfect electrical connection between the said lever and frame, while at the same time it acts to return the 5 lever to normal position for breaking contact. An adjusting-screw f' is arranged adjacent to and bearing on the contact-spring f^3 for setting the latter relatively to the contact-point f^2 on the lever and thus regulating the 10 contact. Whenever the platinum point f^2 of the contact-lever F^2 is pressed against the spring f^3 , the circuit with the driving battery is closed, so that the current of the same passes from one pole of the battery to the 15 clock-frame, then through lever F^2 to the insulated contact-spring f^3 , thence through the clamping-clip f^4 and suitable metallic connections to the coils of the electromagnet E, and then back to the other pole of the battery. 20 (See Fig. 22.) As soon as the circuit is closed the current energizes the electromagnet, so that the poles of the same attract the armature E' and impart a turning motion to the same on its spindle and thereby through the 25 crutch C an impulse to the pendulum.

Upon the arbor d of the crutch C of the pendulum P is applied a cross-piece g, that carries two gravity push-pawls $g' g^2$, which are pivoted to the cross-piece at opposite points 30 and equidistantly from the spindle d, said cross-piece being secured to the crutch-spindle by a suitable set-screw. The pawls alternately engage the teeth of the driving spur-wheel G, by which, in connection with suitable transmitting-gear, the necessary motion 35 is imparted to the arbor of the minute-hand and from the same by the usual transmitting mechanism to the arbor of the hour-hand.

When the push-pawls and driving spur-wheel are used in a clock-movement having 40 a seconds-hand, the spur-wheel G is applied directly to the arbor of the seconds-hand, the pawls being arranged so as to work in the same plane with the spur-wheel, as shown in 45 Fig. 3. When used in a clock-movement without seconds-hand, the motion-transmitting beveled gear-wheel, as shown in Fig. 3, is dispensed with, and pawls of special shape that engage the teeth or notches in the side 50 of the spur-wheel G are used, said spur-wheel having in this case a horizontal or nearly horizontal position on its arbor, as shown in Fig. 12. In the place of the horizontally-projecting teeth on the spur-wheel G the teeth 55 may be bent up at an angle with the plane of the wheel, so as to form a crown-wheel with ratchet-teeth by which the driving motion is imparted to the clock-train.

By the double-push-pawl device described 60 a forward motion is imparted to the hands at each beat of the pendulum, the advance of the spur-wheel being one-half tooth for each single beat of the pendulum. This result is obtained because while one pawl engages the 65 spur-wheel the other moves backwardly over a tooth of the spur-wheel, and vice versa. By this arrangement it is possible to give a cor-

rect motion to the seconds-hand, so as to divide the minute properly, as indicated on the seconds-dial. With the use of a single driving-pawl in conjunction with a fixed check-pawl motion would be imparted to the hands by the driving-pawl only once for each alternate beat, so that in a clock having a pendulum of length to beat seconds, or sixty times 75 per minute, the seconds-hand would only be moved thirty times per minute, or once every two beats of the pendulum. By using the double push-pawl, however, the minute is accurately divided into seconds, and the seconds-hand is moved with each beat of the pendulum. The same proportion is maintained when using shorter pendulums—as, for instance, with an eighty-beat pendulum the minute is divided by fractions less than seconds by this device, so that the time may be accurately measured by the seconds-hand, whereas the single drive-pawl would give only forty motions per minute, or more than one second for each motion of the seconds-hand. By employing the double-push-pawl device the check-pawl may be dispensed with, as each pawl acts in its turn as a check-pawl for the other pawl. Furthermore, the work of the pendulum is more evenly divided, inasmuch as it moves the clock-train forward at every beat instead of by every second beat. This produces also a more frequent movement of the minute-hand, which is an advantage, especially in the case of large 90 clocks having long hands, so as to make the advancing motion of the minute-hand less noticeable.

The synchronizing device by which the hands are electrically set at certain intervals 105 of time, so as to be placed in synchronism with a master or other clock, is composed of two separate and independent mechanisms, one for setting the minute-hand and the other for setting the seconds-hand. In clocks 110 without seconds-hands the latter mechanism is not required, while for clocks having seconds-hands both the mechanism for synchronizing the minute and seconds hands are 115 used.

The minute and hour hands synchronizer is composed of a bar electromagnet M, which is provided with a soft-iron armature projecting through its supporting-bracket M^0 , which is attached to the front plate of the 120 clock-frame. A plate M' , forming the outer clamping part of this bracket, extends upward and serves as a bearing for the arbor of the intermediate gear-wheels, by which the motion of the minute-hand is transmitted to 125 the arbor of the hour-hand. The rear and front parts of brackets $M^0 M^X$ leave thus a space above the pole-face of the core of the electromagnet in front of the front plate of the clock-frame, so as to permit an armature 130 M' , which is made in the shape of an arm and provided with an enlarged lower end, to move through said space in following the movement of the minute-hand arbor, to which said

armature is rigidly applied. The armature M' is arranged diametrically in line with the minute-hand and applied by a brass clip m to the arbor of the minute-hand, as shown 5 clearly in Fig. 2.

In place of the bar electromagnet a horseshoe or bipolar electromagnet may be used, in which case the armature has to be attracted by the combined means of the pole-10 faces, so as to sweep across the same. The armature M' is located on the arbor of the minute-hand back of the dial, so that it is not seen during the rotation of the minute-hand.

15 The described method of supporting the transmitting gear-wheels by which the motion is transmitted from the minute-hand arbor to the hour-hand sleeve, as shown in Fig. 2, leaves a sufficient clearance for the armature M' as the same moves around with the minute-hand, which would not be the case if said gear-wheels were arranged in the usual manner upon the front plate of the clock-frame.

20 The coil of the electromagnet M is connected with a suitable electric battery W and with a main wire, which is connected with a suitable switch S, as shown in the diagram Fig. 22. The switch is either worked in the 30 usual way by hand, whenever it is desired to synchronize the clocks, or automatically by being connected electrically with a master-clock. The closing of the circuit and the time-signals are given exactly at the even hour.

35 In case the clock to be synchronized should be a little too fast or too slow, the momentary closing of the switch causes a current to flow through the electromagnet M, so as to energize the core of the same and attract the enlarged end of the armature, so as to set thereby the hand to point exactly to the even hour—namely, “12” or “zero”—as the armature is attracted and placed with the hand into vertical position by the pole 40 end of the electromagnet. The armature M' may be adjusted laterally on the arbor of the minute-hand by means of set-screw m', so as to be slightly adjusted relatively to the position of the minute-hand, so that when it is 45 exactly at rest or at the dead-point over the pole face or faces of the electromagnet the minute-hand will point exactly to “12” or “zero.” The armature M' is also capable of adjustment in longitudinal direction, as its 50 upper end is attached by a screw m² to a socket on the clip m, as shown in Figs. 20 and 21, so as to bring the enlarged lower end of the armature as close as possible to the pole face or faces of the electromagnet without 55 touching the same, reducing thereby the air-space between them to a minimum. As the closing of the switch takes place for only a fraction of a second, the armature is immediately released again from the attraction of 60 the electromagnet M, so that the minute-hand is at liberty to move over the dial as before. The minute-hand arbor is thus free

to be moved by the synchronizing electromagnet without interfering with the action of the clock-movement on account of the usual friction-spring device, the tension of which is preferably as light and even as possible. The armature M' serves also as an internal concealed counterpoise for the minute-hand, so as to do away with the unsightly external 70 visible counterpoise which is usually employed on the hands of large clocks. The armature is preferably made of the same weight as the minute-hand, so as to balance the same and permit thereby the easy movement 80 of the minute-hand on its arbor.

The seconds-hand synchronizing device is in the same circuit with the synchronizing mechanism for the minute and hour hands, so that both sets are actuated at the same instant. The seconds-hand synchronizer consists of a specially-shaped thimble n², which is attached to the outer end of the seconds-hand arbor which carries the seconds-hand, so that the two parts turn together, the whole 90 being mounted upon the front end of the seconds-hand arbor either by the usual friction and tension device or by means of the mechanism shown in Figs. 14 to 17. The thimble n² is cut away at one side, so as to form a slot 95 in which rests one leg of a U-shaped tension-spring n³, which bears upon the seconds-hand arbor, while the opposite leg bears upon the outer surface of the thimble. This U-shaped spring by abutting against a shoulder or enlargement n' on the seconds-hand arbor serves to keep the parts on said arbor and furnishes at the same time the required tension and friction, which may be averaged according to the stiffness of the spring employed. The 105 thimble n² is provided with a cam portion n, having converging and slanting cam-faces n^X, that are engaged by a knife-edge, roller, or other device o, which is applied by a shank and set-screw o' into a socket of an armature 110 P' (see particularly Figs. 18 and 19) of an electromagnet P'', which is supported by an extension-bracket attached by fastening-screws to the front plate of the clock-frame. The armature P' is hinged at the outer end of the extension and actuated by means of a spring p^X, so as to keep it away from the pole-face of the 115 projecting core of the electromagnet. The electromagnet may be made in the shape of a bar magnet with single pole or in the shape 120 of a horseshoe with two poles or in any other shape. The extent to which the armature may move away from the pole-face of the electromagnet is regulated by a stud P², having an enlarged end P³, which passes through a 125 slot P⁴ in the armature, said stud being applied to the bracket or extension of the frame. The headed stud P² together with the guide-slot in the armature serve to guide the armature, so as to prevent any lateral play of the 130 same in its forward-and-backward motion when attracted or released by the pole. The knife-edge is applied to the inwardly-projecting end of the armature, which is made long

enough so as to extend to a point directly opposite the cam-faced friction-thimble n^2 on the arbor of the seconds-hand. When the armature is attracted by the closing of the 5 circuit and the energizing of the pole of the electromagnet, the knife-edge or roller will bear on either one of the inclined or cam faces of the friction-thimble and turn it around, carrying the seconds-hand with it until the 10 limit of motion is reached, when the knife-edge or roller arrives at the converging inner ends of the inclined, slanting, or cam faces and can go no farther, as shown in Fig. 7. When the seconds-hand is therefore at either 15 side of the zero or sixty-seconds point of the seconds-dial, the action of the armature on the cam-faces of the friction-thimble will move it exactly up to zero and thereby synchronize the seconds-hand simultaneously 20 with the minute-hand. As the switch is immediately opened again after being closed, the current is interrupted and the armature moved out of engagement with the friction-thimble, so that the seconds-hand can move 25 on in the usual manner.

For the purpose of retaining the uniform working of the batteries employed for supplying the current to the clock two or more batteries W are preferably used, the poles of each 30 of which are connected with segmental sections r , which are applied to the minute-hand arbor, so as to form a kind of automatic switch by which the current is applied alternately from one battery or the other at regular 35 intervals of time. If three batteries are employed, as shown in Fig. 22, the three projecting segments are arranged on the sleeve V of the minute-hand arbor, as shown clearly in detail in Figs. 8, 9, 10, and 11. In this case 40 the segments are applied to the hub of the center wheel, which extends in the form of a sleeve over the minute-hand arbor. The raised segments on the sleeve V are arranged parallel with each other and extend circumferentially around the sleeve, but are located at different points on the circumference of the same, they being of a length slightly less than one-third of the circumference of the sleeve, so that spaces or intervals are formed between 45 the planes of the adjacent ends of the segments. The segments are thereby arranged in such a position to each other that only one at a time is engaged by one of three contact-brushes T , which are applied to an insulating-block T' , that is pivoted to the frame of the 50 clock between the front and intermediate plate of the same, as shown in Figs. 2, 3, 8, and 9. The contact-brushes T are non-elastic and rigidly attached to the insulating-block, 55 which latter is actuated by a tension-spring t , so that the brush which is in action presses evenly against its corresponding segment on the sleeve V . The contact-brushes are each connected with the poles of the three batteries, 60 the enlarged ends extending vertically over the center of the sleeve, so that each forms contact with the segments r on the same as

the sleeve is rotated. During the rotation of the sleeve V one segment r after the other is brought into contact with its contact-brush, 70 so that at the instant one battery is cut out of the circuit the next is switched in and at no time more than one battery is in circuit. This is accomplished by the brushes, as immediately when one contact-brush drops off 75 from the end of its segment the next one drops onto the forward end of its segment. The segments project far enough above the sleeve V so that the brushes will not touch it when dropping from one segment to the next. The 80 object of changing from one battery to the other is to give each battery a chance to rest and recuperate at regular intervals, so as to prolong thereby the life of the batteries and increase their effectiveness. When three batteries 85 are used in connection with springs having three segments, each battery supplies current for twenty minutes and rests forty minutes during every hour.

It is evident that without departing from 90 the scope and spirit of the invention the synchronizing of the minute-hand need not necessarily be obtained at "12," for by setting the operating-electromagnet and the armature at different angles to the arbor of the minute-hand the same may be accomplished at a different time. 95

Having thus described my invention, I claim as new and desire to secure by Letters Patent—

1. The combination, with the minute-hand arbor, of a synchronizing electromagnet, and an arm extending radially from the said arbor and provided at its outer end with an armature, adapted to be attracted by said magnet for moving the minute-hand forward or backward to a given point of time so as to synchronize with a master or other clock, substantially as set forth. 105

2. The combination, with the minute-hand arbor, provided with a minute-hand, of a synchronizing electromagnet, and an armature applied to the said arbor diametrically in line with the said minute-hand and acting as a counterpoise, said electromagnet being arranged in the circle described by the armature, substantially as set forth. 110

3. The combination, with the arbor of the minute-hand, of a synchronizing electromagnet located adjacent to the same, an armature extending radially from said arbor, and means for adjusting said armature longitudinally to and from the arbor and toward the pole of the electromagnet, said magnet and armature co-operating to produce the forward or backward motion of the minute-hand and the synchronizing of the same with a master or other clock, substantially as set forth. 120

4. The combination, with the arbor of the minute-hand, of a synchronizing electromagnet located adjacent to the same, an arm extending radially from the said arbor, means for adjusting the arm around the arbor, an armature, and means for connecting the ar- 125

mature with said arm and longitudinally adjusting the said armature toward the pole of the electromagnet, said magnet and armature producing the forward or backward movement of the minute-hand to the desired point of time, substantially as set forth.

5. The combination, with the clock-frame provided with a supporting-bracket, of a synchronizing electromagnet attached to the bracket, a plate forming the outer clamping part of the bracket, and provided with bearings for the intermediate transmitting mechanism of the hour-hand, said bracket and plate providing a space between them, and 10 an armature attached to the arbor of the minute-hand and adapted to move through said space, substantially as set forth.

15 6. The combination, with the seconds-hand

arbor, provided with a friction-thimble having a tubular cam portion with converging 20 cam-faces on its end, whereby the cam portion is formed with a point and with a notch on its opposite side, and means for applying said thimble to the seconds-hand arbor, of a synchronizing electromagnet, and an armature provided with means for engaging the cam-faces of said friction-thimble, substantially as set forth.

In testimony that I claim the foregoing as my invention I have signed my name in presence of two subscribing witnesses.

SIGISMUND FISCHER.
